United States Patent Office.

S. F. EMERSON, OF SEVILLE, OHIO.

Letters Patent No. 99,301, dated February 1, 1870.

IMPROVED MEAT AND VEGETABLE-CHOPPER.

The Schedule referred to in these Letters Patent and making part of the same.

To all whom it may concern:

Be it known that I, S. F. EMERSON, of Seville, in the county of Medina, and State of Ohio, have invented certain new and useful Improvements in Meat and Vegetable-Choppers; and I do hereby declare that the following is a full, clear, and exact description of my invention, reference being had to the accompanying drawings, forming part of this specification, and to the letters of reference marked thereon, of which drawings—

Figure 1 is a plan of my machine.

Figure 2 is a side view of the same.

Figure 3 is an end view of the same.

My invention consists, first, in operating a vertical chopping-knife in a meat-chopper, by means of a slotted knife-beam, having the knife-standard attached at one end, and having its axis of motion in a pivot at the other end, and operated by means of an eccentric working in the slot in said beam, whereby I offset the mechanical disadvantage due to applying the power between the fulcrum or pivot of the knife-beam, and the resistance of the knife in chopping, by the mechanical power due to the wedge-like action of the eccentric in forcing down the knife, thus making the machine easy to operate, and very compact in construction.

My invention consists, secondly, in so constructing and arranging the knife-standard for a vertical chopping-knife in a meat-chopper, as that the same shall be held at all times during the movements, at three separate points, triangularly arranged in the plane of the knife-standard, two of said points being on the pivot uniting the knife-standard with the knife-beam, and the third point being on a standard secured on the frame outside of the meat-tub, whereby the knife can be so arranged as to move in nearly a vertical plane, passing through the centre of the meat-tub, and is firmly held from wobbling without cramping or impeding its movements.

My invention consists, thirdly, in the combination of a pivoted guide-rod with the knife-standard and frame of a vertical-chopping meat-chopper; said rod being arranged parallel to the knife-beam, and having the distance between its pivots equal to the distance between the pivots of the knife-standard and the pivot of the knife-beam, whereby the knife is made steady in its movements, and is caused to move nearly directly up and down in the meat-tub, thus greatly lessening the liability of throwing the meat out of the tub.

My invention consists, fourthly, in providing the knife-beam with a forked arm, to vibrate a pivoted lever on the frame, to the lower end of which is attached a drag-rod, which engages with a toothed rim on the meat-tub, and imparts a rotary motion to said

tub; the peculiar utility of this arrangement consisting in its simplicity of construction, and its central position in the frame, which protects it from injury, as well as in the facility which it affords for changing the amount of rotary movement in the meat-tub, by simply altering the distance between the drag-rod and axis of the pivoted lever.

My invention consists, fifthly, in extending the sides of the knife-standard up above the pivot on the knife-beam, and uniting them by a bar so constructed as to serve both as a brace to the standard and a handle for the same, whereby the knife is made much more convenient to handle, without increasing its weight or cost.

To enable others skilled in the art to make and use my invention, I will proceed to describe its construction and operation.

In the annexed drawings—

A represents the base-plate of the machine, on which are secured the frame-pieces B B, side-arm G, and centre-pin F, as shown.

The meat-tub consists of the wooden bottom E, circular rim C, and ratchet-rim D, secured on its lower side, and is arranged to revolve on the centre-pin F, which fits in a hole in the bottom E.

The knife-beam M is pivoted at its rear end, between the frame-pieces B B, by means of pivot-pins in the frame-pieces, which fit in the holes m, (see fig. 2,) in the cross-arm Y at the end of the beam M, as shown in fig. 1.

The slot N, which is made with two of its sides parallel, is formed at or near the centre of the beam M, and in it is placed the eccentric O, which is made of a diameter equal to the distance between the parallel sides of the slot N, and is secured on the shaft P, which is arranged in the frame-pieces B B.

The fly-wheel L is secured on the shaft P, together with the pinion V, which meshes into the wheel S on the shaft Z, which shaft is arranged in the frame-pieces B B, and is provided with the crank T, as shown.

The forked arm Q is secured on the beam M, and between its forks is the bent end of the lever R, which is pivoted by a screw, n, to the inner face of the rear frame-piece B, and has the rod W secured to it by a screw or bolt passing through the end of the rod into one of the holes p in the lever, as shown in fig. 2.

The end of the rod W is made with a hook-head, j, which slides on the arm G, and is pressed up to the ratchet-rim D by the spring h secured on the rod W, and pressing against an arm, r, on the arm G.

The knife-standard consists of the two side-pieces J J, which are extended up above the pivot-pin f, and are united by the handle-shaped piece K, as shown in fig. 3.

The knife bed-plate a is secured to the lower ends

of the side-pieces J J, and has the knife b secured to it by means of the screws c c, which pass through slotted holes in the knife, and screw into the bed-plate a.

A flange is formed on the bed-plate a, over the knife b, and the screws d d are passed through this flange and press down on the back of the knife b, thus serving to adjust the knife, so as to cause it to cut squarely on the wooden bottom E of the meat-tub.

The arm I is secured on one side-piece J of the knife-standard, and projects over the side C of the meat-tub, where it is provided with a flange, t, which has a hole formed in it for the guide-rod H, which is secured in the arm G, as shown in fig. 3.

The broad, flat wings X X are secured on the bed-plate a over the knife b, and serve to prevent the meat which sticks to the knife from being thrown over the side C of the meat tub, by the upward movement of the chopping-knife.

The knife-standard is secured to the knife-beam M by means of the pivot-pin f, which passes through a side-piece, J, on one side of the beam M, through the arm e at the end of said beam, and through the side-piece J on the other side of said beam, as shown in fig. 3.

The pivoted guide-rod U is pivoted at its rear end to an arm, l, on the frame-piece B, and its front end is made in a straight hook-form, and hooks on to the pin g in the knife-standard J K J, the rod U being so constructed and arranged as that a line drawn from the pin g to the pivot-pin in the arm l shall be equal in length and parallel to a line drawn through the beam M, from the centre of the arm e to the centre of the arm Y, (the axis of said arms being supposed to be the axis of motion of the knife-standard on the knife-beam, and of the knife-beam in the frame B B.)

From the foregoing description, it is readily seen, that by turning the crank T a reciprocating motion will be imparted to the knife b, by which it will be caused to chop the meat placed in the tub C E, and that the reciprocating movements of the rod W will cause an intermittent rotation of the tub C E, thus bringing the meat in all parts of the tub under the action of the knife; the amount of rotation in the meat-tub being varied, to suit different degrees of fineness required in the meat, by changing the bolt or screw which unites the rod W to the lever R, from one hole p to another, in a manner readily understood.

It is also evident that the knife-standard J K J is held, during all its movements, by the two bearings of the pivot-pin f, in the side-pieces J J, and by the bearing of the rod H in the end t of the arm I on the knife-standard, these three bearing points being triangularly arranged in the plane of the knife-standard, and hence acting together to prevent any wobbling of the knife.

The pin f can be easily drawn out, when the knife-standards can be readily lifted from the rod H and

hopper C E, by means of the handle K, as is readily seen.

It is evident that the rod U could be arranged below the beam M, if preferred, and that the guide-rod U and the arm I and rod H can be used either separately or in combination, to steady the knife-standard, care being taken, when both devices are used in combination, that the rod H be curved to conform with the arc described by the pivot-pin f.

Having thus fully described my invention, I do not claim as new the hanging of a chopping-knife standard at the end of a walking-beam, nor do I claim the use of a knife-standard, except when combined with the mechanism described, or when constructed with the handle-piece, as shown; nor do I claim the intermittent rotation of the meat-hopper, except when produced by the combination of mechanism shown; nor do I claim the use of the arm I and rod H, except in combination with the pivot-pin f, and then only when the several parts are arranged in the same plane, as shown; but

What I do claim herein as new and of my invention, and desire to secure by Letters Patent, is—

1. The combination of the knife-beam M, provided with slot N, and vibrating around suitable journals at one end, knife-standard J J, and the eccentric O, arranged on shaft P, and working in slot N, the several parts being constructed and arranged to operate as and for the purpose specified.

2. The knife-standard J J, secured on vibrating-beam M by pivot-pin f, and provided with arm I, having a collar, t, to slide on guide-rod H, when said guide-rod is placed outside of the hopper C E, and the bearings of the pivot-pin f in said standard, and the hole in the collar t, are triangularly arranged in the plane of said standard, as and for the purpose specified.

3. The combination of the knife-beam M, knife-standard J, and pivoted guide-rod U, said guide-rod being arranged parallel to the knife-beam, and having the distance between its pivots equal to the distance between the pivot line of the knife-standard, and the axis of vibration of the knife-beam, as is hereinbefore specified.

4. The combination of the forked arm Q, on the knife-beam M, pivoted lever R, drag-rod W, and hopper C E, with ratchet-rim D, the several parts being arranged as is herein specified.

5. The knife-standard J K J a, consisting of the bed-plate a, side-pieces J J, and handle K, uniting the side-pieces J J above the pivot-pin holes in said side-pieces, as and for the purpose specified.

As evidence that I claim the foregoing, I have hereunto set my hand, in the presence of two witnesses, this 27th day of October, 1869.

S. F. EMERSON.
